UNITED STATES PATENT OFFICE.

SAMUEL E. RAHE, OF RICHMOND HILL, NEW YORK.

MACHINE FOR MAKING MATCH CARDS.

Application filed February 9, 1926. Serial No. 87,042.

My invention relates to improvements in machines for making match cards, and more particularly match cards such as are adapted for use in the manufacture of match books, or book matches so called. In the trade a match card comprises a series of splints united to a common base from which they are torn off as needed, and in recent times such cards are usually enclosed in a cover. My invention relates to the manufacture of the match cards without regard to their subsequent use. A greater part of the match cards are at present manufactured from paper stock, and they are cut usually by passing the paper through dies having meshing parts, which push a part of the splints into the grooves of one die, while a part lie in the other. This system operates fairly well on paper, although the cutting is rather ragged, and in the attempt to cut wood veneers this way the result is entirely unsatisfactory, as the wood veneers and the splints are imperfect. Moreover in this system of cutting, the stock strips are long enough for a plurality of cards which are cut usually one by one from the strip.

My invention is intended to obviate these difficulties, and produce a machine which will turn out match cards much more rapidly than at present, and will cut smoothly so that the splints are actually better and far more attractive in appearance. In carrying out this idea I use a stock feed which carries the stock strips through the machine, and provide a series of knives which cut through the stock with a drawing cut so as to leave the splints entirely smooth and therefore my improvements are as well adapted for cutting wood veneers as for cutting paper or other stock. Moreover by this arrangement I arrange my cutting means in such a way that the stock strips are severed into cards at the same time the splints are cut, and finally the cards are placed in the dipping carrier and separated therein so as to be in position for convenient covering at a later operation.

In some respects my present invention is an improvement on and a development of the structure shown in my application for Letters Patent of the United States Serial No. 80,250, filed January 9th, 1926.

In general my invention is intended to produce a machine which will make match cards better and far more rapidly than they have heretofore been made.

Reference is to be had to the accompanying drawings forming a part of this specification, in which similar reference characters indicate corresponding parts in all the views.

Figure 1 is a sectional elevation on the line 1—1 of Figure 4, showing the initial position of the stock feed.

Figure 2 is a view similar to Figure 1 but showing the stock feed in another position.

Figure 3 is an elevation also corresponding to Figure 1 but showing the match cards in the action of having the splints separated and the cards introduced in the carrier.

Figure 4 is a broken plan view of the machine with parts removed.

Figure 5 is a broken cross section on the line 5—5 of Figure 1.

Figure 6 is a detail section showing the stock in the action of being engaged by the cutting means.

Figure 7 is a view similar to Figure 6 but showing the further progression of cutting.

Figure 8 is a view similar to Figures 6 and 7 but showing the completion of the splint cutting.

Figure 9 is a broken cross section on the line 9—9 of Figure 1.

Figures 10 and 11 are detail sections showing the action of the presser foot in shaping the card preparatory to its insertion in the carrier.

Figure 12 is a section on the line 12—12 of Figure 3.

Figure 13 is a perspective view of a match card with the splints in line, and

Figure 14 is a detail view but with the splints separated for dipping.

In this type of machine the cards and splints are cut from strips of stock 10 (see Figures 3 and 4) which are long enough to form a plurality of cards, and the width of which corresponds to the length of the splints and connected base. These strips are cut into cards 11 having splints 12 which are united at one end to a common base 13 from which they are torn one by one and used after they have been formed into matches. The conventional cards are shown in Figures 13 and 14. Referring to Figures 1 to 3 I have shown the machine provided with conventional feed rollers 14 and 15 and with a carrier 16 which is also conventional, and has holding means 17 for the individual cards. The structure is mounted in a suitable frame 18 which can be of any approved design, and

100

105

110

the stock strips 10 are fed one behind the other upon a table 19 (see Figures 1, 2 and 3) with the strips extending transversely of the machine. The table 19 has preferably an 5 inturned inner end 20 (see Figure 1), and the stock strips 10 as they are pushed over the edge of the table, fall upon the stock holder which has an inclined bottom 21 and is formed by a recess in the pusher plate 22 10 which reciprocates back and forth in the machine in a horizontal manner, and which can be moved in any approved way. I have shown the pusher plate connected by bolts 23 to a sliding carriage 24, and as shown in 15 Figure 2 the bolt connection can be through large holes to provide for a certain amount of adjustment of the pusher plate on the carriage. The carriage as illustrated reciprocates in horizontal tracks 25, and it is moved 20 by pitmen 26 which can be actuated in any usual way. The foregoing structure is not here claimed as novel except for the arrangement of the holder on the pusher plate, 25 as I believe it is new to have the holding recess formed with an inclined bottom 21 and with means for scoring the cards, as presently described.

As the pusher plate 22 moves inward in the machine and towards the carrier 16, it 30 carries a stock strip 10 into engagement with the blades 28 and 29 which are arranged in the path of the stock feed and which are preferably of the kind illustrated where the blades follow one another, being united to a 35 common body 30. The blades could have a single edge instead of a double edge as shown, if preferred. These blades are in spaced relation the width of a match splint apart, and can be held in any approved way 40 in the path of the stock, but a convenient means is shown where they are attached to a cross head 31 having its under side recessed as shown at 32 to receive the blades, and a flange 33 in the cutter head serves as a backing 45 for the inner ends of the blades. The cross head is attached to the frame by bolts 34, and the blades 30 are further fastened through bolts 36, while they are spaced by spacer blocks 35 which are placed between 50 the blades as shown in Figure 5. The pusher plate 22 is slotted longitudinally as shown at 27 in Figure 5, so that the blades 28 and 29 can register with the slots, and the inclined stock holder at the end of the pusher plate 55 has wedge shaped ribs 37 which are spaced apart the width of the match splints and which have their thinner ends placed inward so that the stock 10 lying on the ribs 37 as in Figure 1 will be inclined, with the outer end raised and the inner end pitched below contact with the blades 28 and 29. The object 60 of having the holder inclined at top and bottom, that is at the top surface of the ribs 37 and at the bottom of the grooves between the ribs, is to provide for the easy and effi-

cient separation of the splint ends, as presently described.

The holder on the pusher plate is also provided just in advance of the ribs 37 with a transverse shoulder 38 raised slightly with 70 reference to the bottom of the stock holder 21, so as to score the splints transversely at the point where they join the base 13 of the cards, to the end that the splints may be torn off easily, and the presser foot 39 which is used in connection with the stock holder of the pusher plate has a similar shoulder 38' which scores the upper part of the card.

Attention is also called to the fact that at spaced intervals are blades 30' which are in 80 series with the blades 30, but which are deeper, and these blades 30' are spaced apart the width of a match card so that as the stock is pushed through the machine, the blades 30 having the double edges 28 and 29 will cut 85 the splints, while the inner edge of the stock strip as shown in Figures 6 to 8 will pass below the cutting blades, but the longer or deeper knives 30' will extend into the path 90 of the whole stock strip and thus sever it into cards. I have found in actual practice that the character of the stock used in cutting card matches is such that my improved means of cutting can be carried out efficiently and 95 without clogging, as the stock whether paper or thin wood veneers, yields sufficiently to permit the knives or blades which are very thin to pass smoothly through it, and as these blades are pitched or inclined, and the stock is also inclined and moves in a plane intersecting at a small angle the cutting blades, a drawing cut results, and the cut edges of 100 the splints are left exceedingly smooth, which is desirable in the trade, as the matches produced in this way look much better, and are 105 actually stronger.

When the pusher plate 22 and a stock strip thereon has been carried forward as in Figure 2 so as to pass the cutting blades, the cards are then engaged by means for separating the free ends of the splints preparatory to dipping, and this can be easily accomplished by a presser foot 39 which moves up and down with respect to the pusher plate and is adapted to register with the recessed end 21 of the pusher plate, the presser foot having also ribs 40 shaped like the ribs 37 and adapted to fit between them, and obviously there are grooves between the ribs 40 to receive the ribs 37 of the stock holder. The presser foot also has a shoulder 38' to score the splints at their junction with the base 13 of the cards, and when the presser foot descends on the cut cards, it will be seen that as shown in Figures 10 and 11, one half the 110 splints will be pushed into the grooves between the ribs 37, while the other half will be pushed into the grooves between the ribs 40 of the presser foot, while the base 13 of the cards will project beyond the stock holder 115 120 125 130

and presser foot, as shown in Figures 10 and 11, and the machine is timed so that as the cut cards assume this position, the pusher plate 22 will be advanced to the point of inserting the bases of the cards 11 in the holders 17 of the dipping carrier 16, as shown clearly in Figure 3.

The pusher plate 22 and the carriage 24 are then returned to repeat the operation, but 10 attention is called to the fact that at each stroke of the pusher plate, the long stock strip is carried forward, cut smoothly into match splints and match cards, and the cards inserted in the carrier with the splint ends separated ready for dipping. In this way I not only get better match cards and splints, but the operation of producing them is tremendously accelerated over the ordinary practice.

The pressure foot 39 as illustrated can be 20 actuated in any convenient way, and I have shown a means similar to that illustrated in my prior application above referred to for operating it, although in the prior case the presser foot is not like this here shown. The 25 presser foot can be guided in any convenient way, and it is moved up and down by links 41 and 42 which are pivotally connected to it at the ends, and which are also pivotally connected to rocking levers 43, these being pivoted near the center on the shaft 44, while the rear ends of the levers are upturned and carry rollers 45 on a shaft 46. The inner ends of the levers 43 are also upturned and carry rollers 47 on a shaft 48. The rollers 47 30 and 45 are in spaced relation, and are in the path of shoes 49 on the under side of the carriage 24, these shoes being rounded at the ends as shown at 50 so that they will act like cams. Thus as the carriage moves inward 35 with its pusher plate and stock, the ends of the shoes 49 striking the rollers 45 will tilt the levers 43 in a manner to raise the presser foot 39, and as the carriage advances the stock will have been cut by the cutting mechanism 40 described, and the inner ends of the shoes will strike the rollers 47, and the outer ends of the shoes will have pressed the rollers 45, so that the levers 43 will be tilted and the presser foot 39 moved down to act on the cut stock 45 as already described. At the same time that the presser foot completes the depression of the splint ends, the bases of the several cards 50 will have been inserted in the holders 17 of the carrier, which by the way can be any 55 holding means, and I have simply shown the conventional holder.

It is desirable to have the cards separated slightly from each other in the dipping carrier, that is in the holders 17 thereof, for 60 this reason. The trade prefers to have the covers for the cards slightly wider than the cards, and if the cards are separated in the dipping holders, then they are in position to be ejected in such relation to the covers as to 65 obviate the need of any further adjustment.

To provide for this separation I provide in the path of the cards in their holders, means for separating the cards with relation to each other, and I have shown (see Figures 1, 2, 3 and 12) a series of fins or blades 51 70 which are supported on a suitable bracket 52, and extend with their edges opposite the junction of the several cards in the holders 17. These blades have to be of slightly different inclination as shown at Figure 12, but 75 the order of their inclination can be readily ascertained by one operating the machine, and as the cards are carried through the wedges or fins 51, these serve to space the cards ready for ejecting into their covers 80 later on.

From the foregoing description it will be clearly seen that I have provided means for cutting match cards faster and better than heretofore, and it will be understood that 85 many of the details of construction can be departed from without affecting the invention, the important thing being to have the stock strips carried forward by the stock feed and held in relation to the cutting means 90 so that the splints and cards will be all cut at once from the strips, the cutting effected in in a drawing manner so that the edges of the cut parts may be smooth, and the cut splints pressed into shape to separate their free ends. 95 It will also be understood that any suitable carrier can be used for dipping the splint heads.

I claim:

1. A machine for making match cards comprising a stock feed having an inclined stock holder with splint grooves therein, a series of thin spaced blades disposed so as to engage and cut edgewise through the stock for a part of its width thereby forming splints, 100 and a member behind the blades grooved to mesh with the grooves in the holder and arranged to press upon the cut stock in the holder.

2. A machine for making match cards comprising a stock feed having a holder for carrying sheet stock, said holder having grooves therein the width of a match splint apart, a series of thin spaced blades disposed to engage and cut edgewise through 110 the stock for a portion of its width thereby cutting match splints, and a presser foot behind the blades grooved to mesh with the holder and movable with relation thereto, whereby some of the cut splints are forced into the holder grooves and some into the 115 grooves of the presser foot thereby separating the splint ends.

3. A machine for making card matches comprising a stock feed having a holder with 125 splint receiving grooves for carrying sheet stock, a series of spaced thin blades in the path of the stock disposed to engage and cut edgewise through the stock for a portion of its width, and a grooved presser foot behind 130

the blades meshing with the holder whereby the cut splints are forced into the grooves of the holder and presser foot.

4. A machine for cutting match cards comprising a stock feed having an inclined grooved holder for sheet stock, a series of thin spaced blades in the path of the stock, some disposed to cut through the stock for a portion of its width and others to cut through the stock for its full width, and a grooved presser foot meshing with the holder whereby some of the cut splints are forced into the grooves of the holder and others into the grooves of the presser foot.
5. A machine for making match cards comprising a stock feed having means for carrying sheet stock generally edgewise to its cutter, and a cutter having thin spaced blades in the path of the stock, with some of the blades disposed to clear the advancing edge portion of the stock and cut through the remainder, and others of said blades being arranged to cut through the full width of the stock.
6. A machine for making match cards having thin inclined blades the width of a match splint apart forming a unitary cutter, a stock holder in a plane parallel with the blades support, the blades and stock holder being slidable with relation to each other, and means for supporting a stock strip in the stock holder with one edge portion out of the plane of the blades and the body portion in the plane of the blades whereby the said edge portion is uncut and the body portion is cut through into splints.
7. A machine for making match cards comprising stationary thin inclined blades spaced apart the width of a match splint, a stock holder movable opposite and in a plane parallel with the blades, and means for supporting a stock strip on the stock holder with one edge portion out of the plane of the blades and with the remainder of the stock strip in position to be cut through by the blades.
8. A machine for making match cards comprising a series of thin stationary inclined blades spaced apart the width of a

match splint, a stock holder reciprocating opposite and in a plane parallel with the blades, and means for supporting a stock strip in the stock holder with the forward edge portion of the stock strip below the plane of the blades and the remainder of the strip in the plane of the blades.

9. A machine for cutting match cards comprising a series of stationary thin inclined blades spaced apart the width of a match splint, a stock holder reciprocating in a plane parallel with the blades and having an inclined stock supporting face with match splint grooves therein, the stock holder being positioned to hold a stock strip with the forward edge out of the plane of the blades, and a vertically movable presser foot behind the blades and having ribs to engage alternate match splints and force them into the grooves of the stock holder.

10. A machine for making match cards comprising a stationary series of thin spaced inclined blades the width of a match splint apart, a reciprocating stock holder movable in a plane parallel with the blades and having means for supporting a stock strip in an inclined position with one edge projecting below the plane of the blades, said stock holder having splint grooves therein, a presser foot behind the blades moving back and forth with relation to the stock holder and having ribs to force alternate splints into the grooves of the stock holder, and means for scoring the formed splints at their junction with the uncut edge of the card.

11. In a machine for making match cards, the combination with the cutting blades, the reciprocating stock holder having grooves therein, and the presser foot movable back and forth with relation to the stock holder, of means carried by the stock holder and presser foot for scoring the match splints at their junction with the uncut part of the card.

In testimony whereof, I have signed my name to this specification this 8th day of February, 1926.

SAMUEL E. RAHE.
